UNITED STATES PATENT OFFICE

JOSEPH FICKINGER, OF BELLEVILLE, ILLINOIS, ASSIGNOR TO OAKLAND FOUNDRY COMPANY, OF BELLEVILLE, ILLINOIS, A CORPORATION OF ILLINOIS

DESIGN FOR A STOVE

Application filed June 4, 1932. Serial No. 43,980. Term of patent 7 years.

To all whom it may concern:

Be it known that I, JOSEPH FICKINGER, a citizen of the United States, residing at Belleville, county of St. Clair, and State of Illinois, have invented a new, original, and ornamental Design for a Stove, of which the following is a specification, reference being had to the accompanying drawing, forming part thereof.

The figure is a perspective view of a stove showing my design.

I claim:

The ornamental design for a stove as shown.

JOSEPH FICKINGER.
